UNITED STATES PATENT OFFICE

123,565

DESIGN FOR A CHAIR

George C. Brainard, Youngstown, Ohio, assignor to The General Fireproofing Company, Youngstown, Ohio, a corporation of Ohio

Application March 15, 1940, Serial No. 90,968

Term of patent 14 years

To all whom it may concern:

Be it known that I, George C. Brainard, a citizen of the United States, residing at Youngstown, in the county of Mahoning and State of Ohio, have invented a new, original, and ornamental Design for a Chair, of which the following is a specification, reference being had to the accompanying drawing, forming part thereof:

The characteristic features of my design reside in the portions shown in solid lines.

I claim:

The ornamental design for a chair, as shown and described.

GEORGE C. BRAINARD.
